United States Patent Office

Des. 176,241
Patented Nov. 29, 1955

176,241

HELICOPTER OR SIMILAR ARTICLE

James R. Williams, Irving, Tex.

Application June 16, 1954, Serial No. 31,007

Term of patent 14 years

(Cl. D71—1)

fig. 1

fig. 2

fig. 3

Figure 1 is a front elevational view of a helicopter showing my new design.

Figure 2 is a side elevational view; and

Figure 3 is a top plan view.

The sides of the helicopter are identical in design.

I claim:

The ornamental design for a helicopter or similar article, substantially as shown and described.
